United States Patent Office

Des. 178,882
Patented Oct. 2, 1956

178,882

TOLL COLLECTING CABINET OR SIMILAR ARTICLE

Albert Hohmann, Brooklyn, N. Y., assignor to
Benjamin Cooper, Brooklyn, N. Y.

Application May 18, 1955, Serial No. 36,083

Term of patent 14 years

(Cl. D52—3)

FIG.1.

FIG.2.

FIG.3.

FIG. 4

Figure 1 is a plan view of a toll collecting cabinet showing my new design.

Figure 2 is a front elevation of the toll collecting cabinet.

Figure 3 is a side elevation of the toll collecting cabinet.

Figure 4 is a front perspective view of the toll collecting cabinet.

The undisclosed side of the toll collecting cabinet is substantially the same in appearance as the side shown.

I claim:

The ornamental design for a toll collecting cabinet or similar article, substantially as shown and described.
